UNITED STATES PATENT OFFICE.

EMANUEL B. ADLER, OF ALLEGHENY, PENNSYLVANIA, ASSIGNOR TO
HENRY ADLER, OF PITTSBURG, PENNSYLVANIA.

DESIGN FOR A GAS-STOVE.

SPECIFICATION forming part of Design No. 33,653, dated December 4, 1900.

Application filed October 26, 1900. Serial No. 34,610. Term of patent 14 years.

To all whom it may concern:

Be it known that I, EMANUEL B. ADLER, a resident of Allegheny, in the county of Allegheny and State of Pennsylvania, have invented a new and original Design for Gas-Stoves; and I do hereby declare the following to be a full, clear, and exact description thereof, reference being had to the accompanying drawing, in which the figure illustrates a perspective view of a gas-stove embodying my design.

The leading features of my design consist in a gas-stove having the shape and form, as well as the configuration and ornaments, substantially as herein shown and described.

As illustrated in the drawing, 1 represents the sides of the stove, the front 2 of which extends out at an angle to the front base-plate 3, which is secured to the sides 1 and has the front legs 4 secured thereto and to the sides 1. Rear legs 5 are also secured to the sides 1 and back 6, and extending across between the sides 1 above the angular portions 2 and below the top plate 2' is the upper face-plate 7, which has the hood 8 formed thereon and 25 ornamented, as shown. The sides 1, top plate 2', base-plate 3, upper face 7, and hood 8 are formed with the corrugations 9 therein, and said top plate 2' has vertical pipes 2'', opening out of the same. A curved corrugated 30 reflector-plate 10 fits over the top edge of the

base-plate 3 and rests against the burner 11. In the rear of the burner 11 is a plate 12, which has horizontal corrugations therein, and corrugated reflector-plates 13 are also secured on the inside of the side plates 1, in front of and adjacent to the curved corrugated reflector 10.

Fitting down over the top plate 2' is the top or cover 14, which is provided with the flanges 15, extending around the same and fitting down over the sides 1, back 6, and upper face-plate 7, said cover 14 having the upwardly-curved portion 16 thereon, which is provided with a series of openings or perforations 17 therein, and a roll portion 18 is formed on the curved portion 16, on which is secured an ornamental handle 19.

What I claim as my invention, and desire to secure by Letters Patent, is—

The design for a gas-stove, substantially as herein shown and described.

In testimony whereof I have hereunto set my hand, at Pittsburg, in the county of Allegheny and State of Pennsylvania, this 24th day of October, 1900.

EMANUEL B. ADLER.
